(57) **CLAIM**

The ornamental design for a personal digital assistant slide cover body, as shown and described.

DESCRIPTION

FIG. 1 is a rear perspective view of a personal digital assistant slide cover body showing my new design;

FIG. 2 is a top plan view thereof;

FIG. 3 is a bottom plan view thereof;

FIG. 4 is a right side elevation view thereof;

FIG. 5 is a rear elevation view thereof;

FIG. 6 is a left side elevation view thereof;

FIG. 7 is a front side elevation view thereof;

FIG. 8 is a front perspective view thereof;

FIG. 9 is a top plan view of the personal digital assistant slide cover body with broken lines illustrating environment that is not part of the design;

FIG. 10 is a bottom plan view thereof;

FIG. 11 is a right side elevation view thereof;

FIG. 12 is a left side elevation view thereof;

FIG. 13 is a front elevation view thereof;

FIG. 14 is a front perspective view thereof;

FIG. 15 is a rear perspective view of the personal digital slide cover body with broken lines illustrating environment that does not constitute part of the design;

FIG. 16 is a top plan view thereof;

FIG. 17 is a bottom plan view thereof;

FIG. 18 is a right side elevation view thereof;

FIG. 19 is a rear elevation view thereof;

FIG. 20 is a left side elevation view thereof;

FIG. 21 is a front side elevation view thereof; and,

FIG. 22 is a frontal perspective view thereof.

Unornamented aspects shown in the drawings by dashed lines permit attachment of the cover body to a user's clothing.
